US00D574449S

(12) **United States Design Patent**
Webber et al.

(10) **Patent No.:** US D574,449 S
(45) **Date of Patent:** ** Aug. 5, 2008

(54) **ABDOMINAL EXERCISE MACHINE**

(75) Inventors: **Randall T. Webber**, La Jolla, CA (US);
Bruce Hockridge, San Diego, CA (US);
Jeffrey O. Meredith, San Diego, CA
(US)

(73) Assignee: **Hoist Fitness Systems**, San Diego, CA
(US)

(**) Term: **14 Years**

(21) Appl. No.: **29/279,975**

(22) Filed: **May 11, 2007**

(51) **LOC (8) Cl.** 21-02

(52) **U.S. Cl.** D21/675; D21/676

(58) **Field of Classification Search** D21/662,
D21/673, 675, 676, 686, 687; 482/93, 94,
482/95, 96, 97, 98, 99, 100, 133, 135, 140

See application file for complete search history.
